UNITED STATES PATENT OFFICE

KENNETH E. BEMIS, OF GLENDALE, CALIFORNIA

DESIGN FOR A BUILDING STRUCTURE

Application filed June 9, 1931. Serial No. 40,139. Term of patent 14 years.

To all whom it may concern:

Be it known that I, KENNETH E. BEMIS, a citizen of the United States, residing at Glendale, in the county of Los Angeles and State of California, have invented a new, original, and ornamental Design for a Building Structure, of which the following is a specification, reference being had to the accompanying drawing, forming part thereof.

The figure is a perspective view of a build-

ing structure, showing my new design.

The end wall and side wall opposite to the walls of the building shown in the drawing are constructed in conformity with the walls as illustrated.

I claim:

The ornamental design for a building structure as shown and described.

KENNETH E. BEMIS.
